UNITED STATES PATENT OFFICE.

DANIEL L. CHANDLER, OF FITCHBURG, MASSACHUSETTS, ASSIGNEE, BY MESNE ASSIGNMENTS, TO VEND ADS CORP., A CORPORATION OF MASSACHUSETTS.

VENDING MACHINE WITH SPURIOUS-COIN DETECTOR.

Application filed December 7, 1921. Serial No. 520,682.

To all whom it may concern:

Be it known that I, DANIEL L. CHANDLER, a citizen of the United States, residing at Fitchburg, in the county of Worcester and 5 State of Massachusetts, have invented new and useful Improvements in Vending Machines with Spurious-Coin Detectors, of which the following is a specification.

This invention relates to a machine for 10 vending articles and is of a character in which manually operable mechanism is provided which is rendered operable by means of a coin inserted in the casing of the machine.

15 The object of the invention is to provide a simple and effective slot machine for vending articles which will operate only when a coin of predetermined dimensions is deposited therein to deliver one of the articles to 20 the party depositing the coin, but which, in the event that there are none of such articles in the machine, or in the event that any of said articles are not of a predetermined size, will eject the coin from the machine so that 25 the party who has deposited the coin may obtain possession thereof. In the event that the article or articles are of the proper dimensions, the coin will be retained by the machine and the article delivered to the depositor of the coin. If, however, the coin is 30 a spurious coin, or what is known as a blank, the dimensions of which are not the same as the coin which it is planned shall operate the machine, then the article is not delivered 35 to the party operating the machine and the spurious coin is ejected therefrom. The same would be true of any coin whether spurious or not which was of different dimensions from that intended and designed 40 to be used in the machine of this invention. For example, if the machine is designed, as in the present embodiment of my invention, to use a nickel or five cent piece, then if a penny or a dime should be inserted in the 45 machine, the mechanism would not be rendered operative to deliver one of the articles, but would be operative to eject the ten cent piece or the penny from the machine.

The machine of this invention also has an attachment for operating an advertising device which will display a different card or plurality of cards each time the machine is operated.

The mechanism of this invention is all mounted upon the underside of a plate constituting the top of the casing of the machine for convenience in manufacture and repairs.

In the device of this invention the article which is to be vended if it is of a predetermined size renders the mechanism for ejecting the coin from the machine inoperable for that purpose and the coin is deposited in a receptacle provided for that purpose in the machine, but when the articles are exhausted from the machine, or if for any reason they do not feed to the delivery mechanism so as to be ejected from the machine, then the mechanism for ejecting the coin from the machine becomes operative. If no coin is placed in the machine, then the manipulation of the crank whereby the article is ejected from the machine and the coin deposited in the coin receptacle becomes inoperative.

The invention consists in a machine of the character set forth of mechanism which only upon the deposit of a coin in the machine of predetermined dimensions is operable to eject the coin from the machine when the article to be vended is not ejected therefrom, or when the article which is ejected therefrom is of less than a predetermined diameter or size, but which, when a coin of predetermined size is deposited in the machine and the machine ejects an article of predetermined size therefrom, will deposit the coin in a coin receptacle within said machine.

The invention consists in the combination and arrangement of parts set forth in the following specification and particularly pointed out in the claims thereof.

Referring to the drawings:

Figure 1 is a front elevation of the machine.

- Fig. 2 is an underneath plan of the same.
- Fig. 3 is a sectional elevation taken on the line 3—3 of Fig. 2.
- Fig. 4 is a sectional plan taken on the line 4—4 of Fig. 3.
- Fig. 5 is a sectional elevation taken on the line 5—5 of Fig. 2.
- Fig. 6 is a sectional elevation taken on the line 6—6 of Fig. 5.
- Fig. 7 is a detail plan of a cam for the feeler mechanism.
- Fig. 8 is a perspective view of the cam feeler lever.
- Fig. 9 is a sectional elevation taken on the line 9—9 of Fig. 2.
- Fig. 10 is a detail sectional elevation of a part of the detector mechanism taken on the line 10—10 of Fig. 2.
- Fig. 11 is a detail sectional elevation taken on the line 11—11 of Fig. 2.
- Fig. 12 is an inverted perspective view of the coin chute and the slide to which it is attached.
- Fig. 13 is an underneath plan of the carrier slide.
- Fig. 14 is a right hand side elevation of said slide.
- Fig. 15 is a left hand side elevation of said slide.
- Like numerals refer to like parts throughout the several views of the drawings.
- In the drawings, 10 is the casing of the machine and 11 the top of said casing which is rigidly and detachably fastened to the casing and has mounted thereon upon the underside the coin controlling, coin detecting and article feeding mechanisms, and upon the upper side, the magazine 12 for holding the articles to be fed and also the movable advertising device 13. The magazine consists, in the present embodiment of my invention, of a rectangular metal container 14 which is fastened to the top 11. The container is provided with a slidable glass front 15, the upper end of which is locked by a padlock 16 to the upper end of the container. The lower end of the slide 15 engages a notch 17 formed in the upper edge of an arm 18 which extends horizontally along the upper face of the top 11 and thence projects downwardly in the form of a vertical rod 19 and through a receptacle 20 for the coin and into the base 21 upon which the casing 10 is fastened. The rod 19, together with the arm 18, thus act as a lock to prevent the coin receptacle 20 from being withdrawn from the machine by unauthorized persons. A guide member 22 is provided at the rear of the base of the magazine and it is slidably mounted in the top of the casing. This guide member is held in the position illustrated in Fig. 5 when the parts are not being operated, by the rear end of a carrier slide 23 which is slidably mounted on the underside of the top 11 and abuts against a downwardly projecting flange 24 on the guide member 22. Said guide member is also provided on its front edge with a vertical flange 25 which projects downwardly in the rear of the article 26 in a column of articles 27, this being the next to the lowermost article in the column of articles so that when the lowermost article 28 of said column of articles is moved forward by the carrier slide 23 as hereinafter described, the article 26 will drop downwardly into the place formerly occupied by the article 28 when the carrier slide has returned to its normal position, and the article 26 will be prevented from tipping or, in other words, it will be guided to enter the space 29 provided in the carrier slide 23 by the flange 25 of the guide member 22 which will be pressed against said article 26 by means of springs 30 which bear against the flange 25 and act to carry the guide member 22 forwardly and against the article 26 as soon as the carrier slide 23 has moved forward a slight distance. The carrier slide 23 is arranged to slide in ways 31 formed upon the underside of the top 11 and a reciprocatory motion is imparted to said slide to feed the article from the magazine 12 out of the machine by a rod 32 which is slidably mounted in a bearing 33 forming a part of the carrier slide 23. The front end of the rod 32 is provided with a head 34 which has a vertical slot 35 therein in which is slidably located a crank pin 36 fastened to a crank 37 on a shaft 38. The crank shaft 38 is rotatably mounted in bearings 39 and 40 fast to the underside of the top 11 and is prevented from moving longitudinally thereof by said crank and by a collar 41 fast thereto and contacting with the end of the bearing 40. The collar 41 has one end of a spring 42 attached thereto by means of a screw 43, the other end of the spring being attached to the top 11 by a screw 44. A crank handle 45 is fastened to the outer end of the shaft 38 so that by rotating the crank shaft 38 by means of the crank handle 45 a reciprocatory motion will be imparted to the rod 32 by the crank pin 36. The spring 42 acts to rotate the shaft 38 in the direction of the arrow α , Fig. 2, and a pin 46 strikes against the upper surface of the top 11 and limits the distance to which the crank shaft 38 can be rotated by the spring 42. The rod 32 is locked to the carrier slide 23 by a coin 47 when it is dropped into the machine in the following manner:—The coin 47 is dropped downwardly through a slot 48 formed in the top 11, which when the parts are in their normal position, aligns with a slot 49 in the carrier slide 23 as illustrated in Figs. 2, 3 and 4. The coin 47 when dropped into the slot 48 descends into the slot 49 in the carrier slide and rests upon a stop finger 50 as

illustrated in Fig. 3. The stop finger 50 is pivoted at 51, Fig. 2, to the carrier slide 23, and is adapted to alternately engage ears 52 and 53 on a stop plate 54 which is fast to the top 11 whereby the lever or stop finger 50 will be moved to close the lower end of the passage 49 and hold the coin 47 therein, or will be moved to open the lower end of said passage 49 and allow the coin to pass downwardly and out of said passage. When the coin 47 is in the position illustrated in Figs. 3 and 4, it projects into a notch 55 provided in the actuating member or rod 32, and when in that position, lies between the adjacent ends of two oppositely disposed hardened screws 56 and 67 which have screw-threaded engagement with the carrier slide 23 and have fastened to their outer ends a pair of arms 58 and 59 respectively. The arm 58 has a pin 60 fast thereto which projects through a hole in the arm 59 and is slidable therein, and the arm 58 is provided with a projection 62 to which is pivotally connected at 63 a link 64 which is slotted at 65 to receive the free end of a lever 66 which projects through said slot and is pivoted at 67 to the carrier slide 23, the opposite end of said lever 66 being provided with a vertical pin 68 which projects into a cam slot 69 provided in a cam plate 70 fast to a bracket 71 which, in turn, is fastened to the top 11 and is, at all times in the operation of the machine, stationary. The lever 66 is connected by a spring 72 to the link 64. The arms 58 and 59 are split to receive their respective screws 56 and 57 and these screws are rigidly fastened to their respective arms by clamp screws 73 as illustrated in Figs. 3 and 4, so that the adjacent ends of the screws 56 and 57 may be adjusted toward or away from each other and clamped in adjusted position. The radial pin 61 on the arm 58 projects into an orifice 74 provided in a cam plate 75 forming a part of a slide 76 mounted to slide in ways 77 on a bracket 78 fast to the top 11. This slide has fast thereto an auxiliary coin chute 79 which has two vertical passages 80 and 81 provided therein. The passage 80 guides the coin to a coin receptacle 82 and the passage 81 guides the coin into a chute 83, Fig. 5, which empties onto a shelf 84 on the front of the machine and outside the casing 10. The auxiliary chute is positioned with the passage 80 in line with the coin slot 49 when there is an article of the proper size about to be delivered from the machine and also said passage 80 is in alignment with the coin slot 49 when the coin which is to be delivered is of the regulation predetermined dimensions, and the passage 81 is moved into alignment with the coin slot 49 when there is no article delivered from the machine, or when the coin which is put into the machine is not of the regulation predetermined dimensions. To accomplish this result the auxiliary chute is moved longitudinally relatively to the carrier slide 23 to bring the passage 80 into alignment with the lower end of the coin slot 49, or the passage 81 into alignment with said coin slot and this is accomplished in the following manner: If a regulation coin, in the present instance a five cent piece or nickel, is dropped into the machine, the carrier slide 23, as hereinbefore described, will be locked to the rod 32, then upon the crank handle 45 being operated by moving it over toward the front of the machine, the carrier slide 23 and the rod 32 will move together as one piece, and the arms 58 and 59 will be rocked downwardly, Fig. 2, by the link 64, spring 72, lever 66, pin 68 and cam plate 70, the action being as follows:—When the carrier slide 23 is moved forwardly as hereinbefore described the pin 68 will travel with it toward the front of the machine, see Fig. 2, and will move in the cam slot 69, rocking the lever 66, the end of which projects through the slot 65 in the link 64, and by the spring 72 the link 64 will be drawn toward the right, Fig. 2, thus tipping the arm 58 and its radially extending pin 61 downwardly in said figure and at the same time tipping the arm 59 downwardly, the two being slidably connected relatively to each other by the pin 60. This will cause the screws 56 and 57 which are respectively left and right-handed screws, to approach and grip the coin 47 with a positively applied yielding pressure. If the coin is of predetermined size, in other words, a regulation standard coin, such as a nickel in the present instance, the arms 58 and 59 will tip downwardly to a sufficient extent so that the radial pin 61 will pass along the orifice 74, see Fig. 11, in the direction of the arrow b. The pin 61 will clear a tooth 85 and will pass beneath said tooth and above a shoulder 86 forming a portion of the lower edge of said orifice. Thus the slide 76 to which the coin chutes 80 and 81 are attached will remain stationary and when the carrier slide has arrived at its extreme forward position, the coin will be released by the action of the lever 66 which being operated by the pin 68 is moved to cause the end which projects into the slot 65 to move toward the left, Fig. 3, thus eventually abutting against the left hand end of the slot 65 and through the link 64 causing the arms 58 and 59 to be moved upwardly and the screws 56 and 57 to move away from each other, thus releasing the coin which will drop into the chute 80 and be delivered into the receptacle 20, then when the handle 45 is released, the spring 42 will cause the parts to be returned to their original positions.

If instead of the coin being a standard coin of predetermined dimensions it is thicker than the standard dimensions, it is evident that upon the machine being operated as hereinbefore described, the arms 58 and 59 could not move downwardly as far as in the case where a thinner standard coin was in use. In such a case the ends of the screws 56 and 57 would abut against the spurious coin before the radial pin 61 had moved downwardly to a sufficient extent to clear the tooth 85 so that said pin 61 would engage the tooth 85 and move the slide 76 and the auxiliary coin chute 79 thereon so that when the arms 58 and 59 were operated at the end of the forward movement of the carrier slide to move upwardly and release the spurious coin, it would drop into the chute 81 and from thence would pass onto the chute 83 and out onto the shelf 84.

If instead of a standard coin being used a coin thinner than the standard coin were placed in the machine, but of substantially the same diameter, the parts would operate as hereinbefore described, except that in this case the arms 58 and 59 would be tipped downwardly to a greater extent than in either of the prior cases, that is, to a greater extent than would be the case where a standard coin was employed, and in this case the radial pin 61 would move downwardly into alignment with the shoulder 86 on the cam plate 75 and thus again upon further forward movement of the carrier slide, the slide 76 would be moved forwardly together with the auxiliary coin chute 79 and the coin would be dropped as hereinbefore described and fall into the chute 81, thence passing onto the chute 83 and out of the machine onto the shelf 84.

If the coin which is dropped into the machine is of a smaller diameter than a five cent piece and is thinner than a five cent piece, as, for example, a dime, then the coin would not project into the notch 55 in the rod 32 and, therefore, the rod 32 and the carrier slide would not be locked together. In a case of this sort when the crank handle 45 is operated, the rod 32 will move forwardly and the carrier slide 23 will remain stationary and when the rod has been brought to its extreme forward position in this manner, the stop finger 50 will be engaged by an arm 87, see Fig. 9, which is provided on a bracket 88 fast to the head 34. This arm 87 as the rod 32 is moved forwardly as hereinbefore described, enters a slot 89 in the carrier slide 23 and engages the stop finger 50 moving it on its pivot 51 and thus allowing the coin or blank to drop out of the coin slot 49, and into the coin chute 81, see Fig. 5, which will allow the coin to pass downwardly onto the chute

83 and out onto the shelf 84 returning the 65 same to the operator of the machine.

Article feeding mechanism.

The lowermost article 28 in the column of articles 27 rests upon a plate 90, Fig. 12, which is fastened to an extension 91 which extends rearwardly from and forms a part of the slide 76 to which the auxiliary coin chute 79 is fastened. This plate 90 remains stationary therefore when the auxiliary coin chute is stationary, the auxiliary coin chute moves when a spurious coin or blank is inserted in the machine, and therefore, no article is delivered from the machine under such circumstances. When, 80 however, a coin of standard size is placed in the machine as hereinbefore described the coin chute will remain stationary and the article will be carried forward by the carrier slide until it has passed beyond the plate 85 90 whereupon it drops out of the carrier slide and down onto a stationary shelf 106 as shown in dotted lines, Fig. 5. The carrier slide has depending therefrom a pusher 107 which is rigidly fastened thereto 90 and when this pusher returns with the carrier slide to its normal position, it will push the article 28 off of the shelf 106 whereupon said article will drop onto the chute 83 and be delivered to the shelf 84 95 on the outside and at the front of the casting. A feeler finger 92, see Figs. 2, 6 and 8, is pivoted at 93 to the carrier slide 23 and has an arm 94 at its free end which projects through a slot 95 in the carrier slide 23 and has a spring 96 connected thereto. When the parts are in the relative positions illustrated in Fig. 2 the extreme free end of the arm 94 is out of engagement with the lowermost article 28 in the column 100 of articles 27 so that said lowermost article is free to drop onto the plate 90 when the carrier slide returns to its normal position. The feeler finger 92 has an upwardly projecting pin 97 fast thereto which projects into an orifice 98 in a cam plate 99 which is stationary and is adjustably fastened by screws 100 to the top 11. As illustrated in Fig. 7 the pin 97 bears against the edge 101 of the cam plate 99 and in this position the free end 94 of the feeler finger is held out of engagement with the article which rests upon the plate 90. When the carrier slide is moved forward as hereinbefore described and there is a standard coin in the machine locking the carrier slide to the rod 32, then the pin 97 will move in the direction of the arrow *c*, Fig. 7, until it leaves the edge 101 whereupon the feeler finger will be moved by the spring 96 until its free end engages the article 28. Upon a further movement forward of the carrier slide and as the article is being pushed off

of the plate 90, the pin 97 will engage the cam edge 102 and the feeler finger 92 will then be rocked to carry its free end away from and out of engagement with the article 28, thus releasing the article 28 and leaving it free to be pushed off of the plate 90 and to fall onto the chute 83 to be guided thereby downwardly and out of the machine onto the shelf 84. At the same time 10 a projection 103 on the feeler finger 92 will be moved out of alignment with an ear 104 which projects laterally from the extension 91 on the auxiliary coin chute slide. When the carrier slide is released and allowed to return to its normal position, the 15 machine is ready for another operation.

Assuming now that a spurious coin of dimensions different from that of the standard coin is introduced into the machine, 20 then upon a movement forward of the carrier slide, the spurious coin will be returned to the operator as hereinbefore described and the auxiliary coin chute slide 76 together with the extension 91 and the plate 25 90 fast to said extension will move with the carrier slide and the plate 90 will remain under the article 28 and the article will return to its previous position at the bottom of the column of articles, but will not be 30 delivered from the machine.

In the event that there is no article to be fed by the carrier slide for any reason whether because there are no articles left in the magazine or because they fail to feed 35 downwardly until the lowermost article is deposited in the carrier slide, then the feeler finger 92 will be moved by the spring 96 inwardly until the pin 97 passes into the position illustrated in dotted lines, Fig. 7, 40 and upon a further forward movement of the carrier slide the pin 97 will pass along the edge 103 of the cam plate 99. This will bring the projection 103 on the feeler finger into alignment with the lateral projection 45 104 on the extension 101 of the auxiliary coin chute slide and upon further forward movement of the carrier slide, said projection 103 will abut the projection 104 and move the auxiliary coin chute so that when 50 the slide is in its extreme forward position and the coin is dropped, it will drop into the chute 81 and pass down the chute 83 onto the shelf 84 thus returning the money to the user of the machine when he does not 55 receive the article which he has paid for. The same would be true if the article were smaller than standard size for in that case 60 the feeler finger would be allowed to project into the position where the projection 97 is in the position illustrated in dotted lines, Fig. 7.

The advertising device is substantially the same as that described and illustrated in application filed by me on September 17, 65 1921 entitled "Vending machine with return

coin mechanism," Serial No. 501,476 and consists of a cylinder 108 rotatably mounted upon the top 11 and within a stationary cylinder 109 fast to the top 11 and provided with a vertical opening 110 through which advertising cards on the cylinder 108 can be seen as said cylinder is rotated step by step as hereinafter described and consisting of a shaft 111 fast to said cylinder 108 and projecting downwardly through the top 11. 70 The said shaft is rotated by a link 112 connected at one end thereof to the carrier slide 23 and at the other end thereof to a pawl carrier 113, said pawl carrier being pivotally mounted upon the shaft 111 and having 75 a feed pawl 114 mounted thereon and adapted to engage a toothed ratchet 115 for the purpose of imparting an intermittent rotary motion to said toothed ratchet which being fastened to the shaft 111, will cause 80 said shaft to rotate in the direction of the arrow *d*, Fig. 2. The shaft 111 is prevented from rotating in a direction reverse to that of the arrow *d* by a locking pawl 116.

When a coin has been deposited in the machine, as illustrated in dotted lines in Fig. 3, and in full lines in Fig. 5, and it rests in the position therein shown, and the operator moves the crank handle 45 to bring the slide 23 forwardly, it is desirable that 90 the slide should be caused to make its full, forward movement before it can return to its rearward position illustrated in Fig. 2, and this desirable result is secured by means described and illustrated by me in said application for Letters Patent and consists of a latch 117 which is pivoted at 118 to the cover 11 and is provided on its under edge with teeth 119 and with an inclined forward portion 120. The latch 117 is held downwardly against a stop screw 121 by a spring 122. It will be seen that the operation of this locking latch is as follows:—When the slide 23 is moved forwardly, the upper edge 100 of the coin 47 will engage the inclined edge 120 and will lift the latch 117 slightly, and upon further forward movement of the carrier slide, the edge of the coin will be engaged by the different teeth 119 which are so shaped as to prevent the slide from returning as long as there is a coin 47 located in the coin slot 49. Upon arriving at 105 its forward position, however, the coin will be pushed down and out of the slot 49 by the action of the spring 122 and the latch 117, thereupon the slide 23 will be free to 110 return to its rearward position.

It will be evident that the carrier slide 23 constitutes a receptacle for an article to be vended and that the rod 32 constitutes a 125 member adapted to be locked to said receptacle by a coin, and in some of the claims these parts, namely the carrier slide 23 and the rod 32 are broadly designated by these terms.

It is evident that without departing from the spirit of my invention the coin chute 80 may be omitted and the standard coin when released by the gripping means allowed to drop into a receptacle located in the casing, and in such a case the coin chute 81 would operate to guide the coin when released from the gripping means to the chute 83 as hereinbefore described.

10 The general operation of the mechanism hereinbefore specifically described is as follows:—

15 1. Assuming the parts of the machine to be in their normal and relative positions as illustrated in the figures of the drawings and that the user drops a coin of predetermined dimensions, in this particular case, a nickel, into the coin slot 48, said coin will pass downwardly through the coin slot 48 into the coin slot 49 and assume the position illustrated in dotted lines, Fig. 3, and in full lines, Fig. 5. The user of the machine then 20 operates the same to pull the crank handle 45 toward the front of the machine. This will operate as hereinbefore described to move the rod 32 and the carrier slide 23 to which said rod is locked by the coin 47 toward the front of the machine. At the same time the end of the lever 50 will be moved 25 out of contact with the ear 52 and all parts which are mounted upon the carrier slide will move therewith, and during this forward movement, the lever 66 will be operated by the pin 68 in the slot 69 to draw the link 30 64 toward the right, Fig. 3, through and by means of the spring 72. This will cause the arms 58 and 59 to be rocked downwardly and thus cause the screws 56 and 57 to be moved toward each other and into contact 35 with the coin 47 with a positively applied yielding pressure. The pin 61 will be moved as hereinbefore described downwardly to clear the tooth 85 and shoulder 86 on the cam plate 75, and as this cam plate which is 40 fast to the slide 76 is the member which moves said slide 76 and the coin chutes 80 and 81 fast thereto, it is evident that the coin chutes 80 and 81 will remain stationary in this operation of the machine under the condition hereinbefore set forth. As the carrier slide is moved still further forward, the 45 pin 67 working in the cam path 69 operates the lever 66 to move the link 64 toward the left, Fig. 3, and thus to rock the arms 58 and 59 upwardly causing the screws 56 and 57 to release the coin 47 and allow the same to drop into the chute 80 from which it rolls downwardly and into the receptacle 20. During this forward movement of the slide, 50 the article 28 is carried forward by the carrier slide pushing the same off of the plate 90, whereupon it drops to the position illustrated in dotted lines, Fig. 5, onto the stationary plate 106. As soon as the handle 55 is released, the spring 42 rotates the shaft 38

to cause the parts to return to the relative positions illustrated in Fig. 2 and during this return movement the pusher 107 on the carrier slide will push the article 28 off of the shelf 106 and the same will drop onto the chute 83 and roll down the same and out onto the shelf 84 where it may be obtained by the operator of the machine. It will be understood that as soon as the carrier slide starts to move forward as hereinbefore set forth, the flange 25 upon the spring actuated guide member 22 will move forward and engage the article 26 and hold the same in the position illustrated in Fig. 5 until the carrier slide returns to its normal position and during the last part of this return movement, the carrier slide will engage the flange 24, and push the guide member 22 and the flange 25 backwardly, thus releasing the article 26 and allowing it to drop into the space 29 in the carrier slide 23 formerly occupied by the article 28.

2. Assuming that no article, such as 28, feeds downwardly from the magazine into the space 29 in the carrier slide 23 and that a user of the machine drops a standard coin into the coin slot as hereinbefore described, in such a case the coin will be returned to the user by reason of the fact that the feeler finger 92 as soon as the carrier slide 23 moves forward, will be allowed to move toward the right, Fig. 2, by reason of the pin 97 on said feeler finger being moved to the position illustrated in dotted lines, Fig. 7, and this movement will bring the projection 103 on the feeler finger 92 into alignment with the lateral projection 104 on the extension 91 of the slide 76 to which the auxiliary coin chute 79 is fastened, then upon further forward movement of the carrier slide, the feeler finger, by means of the projection 103, will engage the projection 104 and push the slide 76 forwardly so that when the coin drops, instead of dropping into the chute 80 and being conveyed into the receptacle 20, it will fall into the chute 81 and from thence will roll onto the chute 83 and out onto the shelf 84 and the customer will thus receive his money back where he has not received value therefor in the shape of one of said articles.

3. Assuming that the user of the machine drops a blank, which is not exactly the same thickness as the coin which it is intended to use in the machine, into the slot 48, the machine will then operate as hereinbefore described to return the coin to the user and no article will be delivered to him by reason of the fact that the arms 58 and 59 will be depressed enough so that the radial pin 61 will engage the tooth 85, or the shoulder 86, in either of which cases the cam plate fast to the slide 76 will move said slide and the auxiliary coin chute thereon so that the coin when released toward the end of the

forward movement of the slide, will be dropped into the coin chute 81 and will pass out of the machine by dropping onto the chute 83 and rolling out onto the shelf 84. At the same time the extension 91 to which the plate 90 is fastened will move forwardly and remain beneath the article 26 and prevent its dropping onto the shelf 106 as hereinbefore described. When the carrier slide is allowed to return to its normal position as hereinbefore described, the article 26 will be carried back to its starting position as illustrated in Fig. 5, the article 28 having been held suspended as hereinbefore set forth by the guide member 22 and its vertical flange 25.

4. Assuming a coin of smaller diameter than the nickel, such as a ten cent piece, is inserted in the machine, it will be returned 20 to the user as hereinbefore set forth, but no article delivered.

I claim:—

1. A vending machine having, in combination, a movable receptacle for an article to be vended, mechanism rendered effective only by the deposit of a coin of predetermined dimensions in said machine and adapted to move said receptacle to feed said article from said receptacle and out of said machine and mechanism adapted to eject said coin from said machine in the event of said article feeding mechanism failing to feed an article as set forth, said last named mechanism including a movable coin directing chute and means for moving said chute to direct said coin out of said machine.

2. A vending machine having, in combination, an article receiving member adapted to receive a coin, mechanism rendered effective only by the deposit of a coin of predetermined dimensions in said machine and adapted to feed said article from said article receiving member and out of said machine and mechanism adapted to eject said coin from said machine in the event of said coin not being of the dimensions aforesaid said last named mechanism including a movable chute, the movement of said chute being controlled by a coin in said article receiving member.

3. A vending machine having, in combination, a receptacle for an article to be vended, mechanism rendered effective only by the deposit of a coin of predetermined dimensions in said machine and adapted to feed said article from said receptacle and out of said machine and mechanism adapted to eject said coin from said machine in the event of said article feeding mechanism failing to feed an article, said mechanism also being adapted to eject said coin from said machine in the event of said coin not being of the dimensions aforesaid, said last named mechanism including a movable chute, and means for moving said chute to direct said

coin out of said machine in the event of said article feeding mechanism failing to feed an article and also in the event of said coin not being of the dimensions aforesaid.

4. A vending machine having, in combination, a receptacle for an article to be vended, and a member adapted to be locked to said receptacle by a coin deposited in said machine, said parts when so locked together being adapted to be moved simultaneously to feed said article from said receptacle and out of said machine, and coin testing means on said receptacle and operable upon movement thereof.

5. A vending machine having, in combination, a receptacle for an article to be vended, a member adapted to be locked to said receptacle by a coin deposited in said machine, said parts when so locked together being adapted to be moved simultaneously to feed said article from said receptacle and out of said machine, and mechanism adapted to eject said coin from said machine in the event of said article feeding mechanism failing to feed an article as set forth, and coin testing means on said receptacle and operable upon movement thereof.

6. A vending machine having, in combination, an article receiving member adapted to receive a coin, a member adapted to be locked to said article receiving member by a coin of predetermined dimensions deposited in said machine, said parts when so locked together being adapted to be moved simultaneously to feed said article from said article receiving member and out of said machine and mechanism adapted to eject said coin from said article receiving member in the event of said coin not being of the dimensions aforesaid.

7. A vending machine having, in combination, a receptacle for an article to be vended, a member adapted to be locked to said receptacle by a coin of predetermined dimensions deposited in said machine, said parts when so locked together being adapted to be moved simultaneously to feed said article from said receptacle and out of said machine and mechanism adapted to eject said coin from said machine in the event of said article feeding mechanism failing to feed an article as set forth, said mechanism also being adapted to eject said coin from said machine in the event of said coin not being of the dimensions aforesaid.

8. A vending machine having, in combination, a receptacle for an article to be vended, a member adapted to be locked to said receptacle by a coin deposited in said machine, said parts when so locked together being adapted to be moved simultaneously to feed said article from said receptacle and out of said machine, means adapted to grip said coin while said parts are being moved and mechanism adapted to oper-

- ate said gripping means to release said coin to allow it to drop out of interlocking engagement with said parts when said article is fed out of said machine.
- 5 9. A vending machine having, in combination, a movable member provided with a slot adapted to receive a coin, rotatable means adapted to grip said coin while said member is being moved, mechanism adapted to operate said gripping means to release said coin and means associated with said rotatable gripping means for directing said coin when released.
- 10 10. A vending machine having, in combination, a movable member provided with a slot adapted to receive a coin, rotatable means adapted to grip a coin located in said slot, mechanism adapted to alternately operate said gripping means to grip and release said coin, and means associated with said gripping means for directing said coin when released.
- 15 11. A vending machine having, in combination, a member provided with a recess adapted to receive a coin, a screw on said member adapted to engage one face of said coin and grip it, mechanism adapted to alternately rock said screw in opposite directions to cause the same to engage said coin and to release said coin, and means associated with said screw for directing said coin when released.
- 20 12. A vending machine having, in combination, a movable member, rotatable means thereon adapted to grip a coin, mechanism adapted to operate said gripping means to alternately grip and release said coin, and means associated with said gripping means for directing said coin when released.
- 25 13. A vending machine having, in combination, a movable member, means thereon adapted to grip a coin, a two-way coin chute movable relatively to said movable member and adapted to receive said coin when released by said gripping means and mechanism adapted to operate said gripping means to alternately grip and release said coin.
- 30 14. A vending machine having, in combination, a casing, a movable member, means thereon adapted to grip a coin, a coin chute movable relatively to said movable member and mechanism adapted to operate said gripping means to alternately grip and release said coin, said mechanism embodying means adapted to move said coin chute to receive said coin when released by said gripping means whereby said coin may be guided out of said casing.
- 35 15. A vending machine having, in combination, a casing, a movable member, means thereon adapted to grip a coin, a movable coin chute and mechanism adapted to operate said gripping means to alternately grip and release said coin, said mechanism embodying means adapted to be positioned by said coin to move said coin chute to receive said coin when released by said gripping means whereby said coin may be guided out of said casing.
- 40 16. A vending machine having, in combination, a casing, a movable member, means thereon adapted to grip a coin, a movable coin chute and mechanism adapted to operate said gripping means to alternately grip and release said coin, said mechanism embodying means adapted to be positioned by said coin to move said coin chute to receive said coin when released by said gripping means whereby said coin may be guided out of said casing or to leave said coin chute stationary and out of alignment with said coin when released whereby said coin may remain in said casing.
- 45 17. A vending machine having, in combination, a casing, a movable member therein, a screw on said member adapted to engage one face of a coin and grip it, a stationary cam, mechanism on said movable member operable by said cam to alternately rock said screw in opposite directions to cause the same to grip and release said coin, and means associated with said gripping screw for directing said coin when released.
- 50 18. A vending machine having, in combination, a casing, a movable member therein, a screw on said member adapted to engage one face of a coin and grip it with a yielding pressure and to subsequently release said coin allowing it to drop out of said movable member, and mechanism associated with said movable member for directing said coin when it drops out of said member.
- 55 19. A vending machine having, in combination, a casing, a movable member therein, a screw on said member adapted to engage one face of a coin and grip it with a yielding pressure and to subsequently release said coin allowing it to drop out of said movable member and into said casing, and mechanism associated with said movable member for directing said coin when it drops out of said member.
- 60 20. A vending machine having, in combination, a casing, a movable member therein, a screw on said member adapted to engage one face of a coin and grip it, a movable coin chute, a stationary cam and mechanism on said movable member operable by said cam to alternately rock said screw in opposite directions to cause the same to alternately grip and release said coin, said gripping mechanism embodying means adapted to be positioned by said coin to move said coin chute to receive said coin when released by said gripping means whereby said coin may be guided out of said casing.
- 65 21. A vending machine having, in combination,

- 5 bination, a casing, a movable member therein, a screw on said member adapted to engage one face of a coin and grip it, a movable coin chute, a stationary cam and mechanism on said movable member operable by said cam to alternately rock said screw in opposite directions to cause the same to alternately grip and release said coin, said gripping mechanism embodying means 10 adapted to be positioned by said coin to move said coin chute to receive said coin when released by said gripping means whereby said coin may be guided out of said casing or to leave said coin chute stationary 15 and out of alignment with said coin when released whereby said coin may remain in said casing.
22. A vending machine having, in combination, a casing, a movable member therein, a screw on said member adapted to engage one face of a coin and grip it, an arm fast to said screw, a cam lever, a stationary cam engaging said lever, a link connecting said lever to said arm whereby said screw 25 may be alternately rocked in opposite directions to cause the same to grip and release said coin, and mechanism associated with said screw for directing said coin when released.
23. A vending machine having, in combination, a casing, a movable member therein, a screw on said member, adapted to engage one face of a coin and grip it, an arm fast to said screw, a cam lever pivotally 30 mounted on said movable member, a stationary cam adapted to engage said cam lever, a link connecting said cam lever to said arm, a spring interposed between said cam lever and said link whereby said screw 35 may be alternately rocked in opposite directions to cause the same to grip said coin with a yielding pressure and to subsequently release said coin and allow it to drop out of said movable member, and mechanism 40 associated with said movable member for directing said coin when it drops out of said member.
24. A vending machine having, in combination, a casing, a movable member therein, a screw on said member adapted to engage one face of a coin and grip it, an arm fast to said screw, a cam lever pivoted to said movable member, a stationary cam adapted to engage said cam lever, a link 45 provided with a slot through which one end of said cam lever is adapted to project, a spring connecting said cam lever to said link whereby said screw may be rocked in one direction to cause the same to grip said coin with a yielding pressure and positively rocked in the opposite direction to release said coin, and mechanism associated with said screw for directing said coin when released.
25. A vending machine having, in combination, a casing, a movable member therein, a slide, a coin chute fast to said slide, a projection on said slide, a screw on said movable member adapted to engage one face of a coin and grip it, mechanism adapted 70 to alternately rock said screw in opposite directions to cause the same to grip said coin and to release said coin, said mechanism embodying an arm fast to said screw and adapted to be positioned by said coin to cause said arm to engage said projection and move said slide and the chute thereon to receive said coin when released by said screw, whereby said coin may be guided out of said casing.
26. A vending machine having, in combination, a casing, a movable member therein, a slide, a coin chute fast to said slide, a projection on said slide, a screw on said movable member adapted to engage one face of a coin and grip it, mechanism adapted 75 to alternately rock said screw in opposite directions to cause the same to grip said coin and to release said coin, said mechanism embodying an arm fast to said screw and adapted to be positioned by said coin to cause said arm to engage said projection and move said slide and the chute thereon to receive said coin when released by said screw, whereby said coin may be guided out of said casing.
27. A vending machine having, in combination, a casing, a movable member therein, a pair of oppositely disposed right and left threaded screws on said movable member adapted to engage opposite faces of a coin and grip it therebetween, mechanism adapted to simultaneously rock said screws alternately in opposite directions to cause the same to grip said coin and to release said coin, and mechanism associated with said screws for directing said coin when released.
28. A vending machine having, in combination, a casing, a movable member therein provided with a recess adapted to receive an article to be vended, a slide, means on said slide normally projecting beneath said recess and adapted to support said article and means adapted to be locked to said movable member by a coin whereby movable member may be operated to remove said article from said supporting means and allow it to pass out of said casing.
29. A vending machine having, in combination, a casing, a movable member therein provided with a recess adapted to re-

ceive an article to be vended, a slide, means on said slide normally projecting beneath said recess and adapted to support said article and means adapted to be locked to 5 said movable member by a coin whereby said movable member may be operated to remove said article from said supporting means and allow it to pass out of said casing and means including said coin to lock 10 said movable member to said slide whereby said article may be prevented from passing out of said recess.

30. A vending machine having, in combination, a casing, a movable member therein provided with a recess adapted to receive an article to be vended, a slide, and means on said slide normally projecting beneath said recess and adapted to support said article.

20 31. A vending machine having, in combination, a casing, a movable member therein provided with a recess adapted to receive an article to be vended, a slide, means on said slide normally projecting beneath said recess and adapted to support said article, mechanism on said movable member adapted to grip a coin, mechanism adapted to operate said gripping means to alternately grip and release said coin, said gripping means 25 operating mechanism including means adapted to be positioned by said coin to lock said slide to said movable member, whereby said article may be prevented from passing out of said recess when said movable member is moved.

32. A vending machine having, in combination, a casing, a movable member therein provided with a recess adapted to receive an article to be vended, a slide, means 40 on said slide normally projecting beneath said recess and adapted to support said article, mechanism on said movable member adapted to grip a coin, mechanism adapted to operate said gripping means to alternately grip and release said coin, said gripping means operating mechanism including means adapted to be positioned by said coin to lock said slide to said movable member, whereby said article may be prevented 45 from passing out of said recess when said movable member is moved, said last-named means being adapted to be positioned by a coin of different dimensions to allow said movable member to move independently of 50 said slide whereby said article may be removed from said supporting means and allowed to pass out of said casing.

33. A vending machine having, in combination, a casing, a movable member therein 60 provided with a recess adapted to receive an article to be vended, a slide, means on said slide normally projecting beneath said recess and adapted to support said article, a feeler finger pivoted to said movable member and adapted to project into said recess

and means to operate said feeler finger during the forward movement of said movable member and when no article is in said recess, to engage said slide, whereby said movable member and slide will move together and said article will be prevented by said supporting means from passing out of said machine.

34. A vending machine having, in combination, a casing, a movable member therein provided with a recess adapted to receive an article to be vended, a slide, means on said slide normally projecting beneath said recess and adapted to support said article, a feeler finger pivoted to said movable member and adapted to project into said recess and means to operate said feeler finger during the forward movement of said movable member and when no article is in said recess, to engage said slide, whereby said movable member and slide will move together and said article will be prevented by said supporting means from passing out of said machine, said feeler finger positioning means being adapted to position said feeler finger to clear said slide during said forward movement when an article is located in said recess, whereby said movable member may be moved independently of said slide and said article removed from said supporting means and allowed to pass out of said casing.

35. A machine for vending articles having, in combination, a magazine for articles, mechanism including a movable member adapted to receive one of said articles and a coin and rendered effective only by the deposit of a coin of predetermined dimensions in said member and adapted to feed an article from said magazine and out of said machine and mechanism controlled by a coin in said movable member and adapted to eject said coin from said machine in the event of said coin not being of the dimensions aforesaid.

36. A machine for vending articles having, in combination, a magazine for articles, mechanism including a movable member adapted to receive one of said articles and a coin, said mechanism rendered effective only by the deposit of a coin of predetermined dimensions in said machine and adapted to feed an article out of said machine and mechanism adapted to direct said coin from said movable member and out of said machine in the event of said article feeding mechanism failing to feed an article as set forth.

37. A machine for vending articles having, in combination, a magazine for articles, mechanism including a movable member adapted to receive an article and a coin, said mechanism rendered effective only by the deposit of a coin of predetermined dimensions in said member and adapted to

- feed an article from said magazine and out of said machine and mechanism including a two-way movable chute controlled by a coin in said member and adapted to eject
 5 said coin from said machine in the event of said coin not being of the dimensions aforesaid.
38. A vending machine having, in combination, a magazine for articles, mechanism including an article receiving slide and rendered effective only by the deposit of a coin of predetermined dimensions in said machine and adapted to feed an article from said magazine and out of said machine and
 10 mechanism including a two-way movable chute adapted to eject said coin from said machine in the event of said article receiving slide not having therein an article as set forth.
- 20 39. A machine for vending articles having, in combination, a receptacle for one of said articles and mechanism rendered effective by the deposit of a coin of predetermined dimensions in said machine and by
 25 one of said articles, to feed said articles out of said machine.

40. A machine for vending articles having, in combination, a receptacle for one of said articles, mechanism rendered effective
 30 by the deposit of a coin of predetermined dimensions in said machine and by one of said articles, to feed said articles out of said

machine and mechanism adapted to eject said coin from said machine in the event of said article feeding mechanism failing to 35 feed an article as set forth.

41. A machine for vending articles having, in combination, a receptacle for one of said articles, mechanism rendered effective by the deposit of a coin of predetermined 40 dimensions in said machine and by one of said articles, to feed said articles out of said machine and mechanism adapted to eject said coin from said machine in the event of said coin not being of the dimensions aforesaid. 45

42. A machine for vending articles having, in combination, a receptacle for one of said articles, mechanism rendered effective by the deposit of a coin of predetermined 50 dimensions in said machine and by one of said articles, to feed said articles out of said machine and mechanism adapted to eject said coin from said machine and retain said article in said receptacle in the event of 55 said coin not being of the dimensions aforesaid.

In testimony whereof I have hereunto set my hand in presence of two subscribing witnesses.

DANIEL L. CHANDLER.
